UNITED STATES PATENT OFFICE.

WILLIAM CURTIS CLARK, OF SAN FRANCISCO, CALIFORNIA, ASSIGNOR, BY MESNE ASSIGNMENTS, TO ACME CARD SYSTEM COMPANY, OF CHICAGO, ILLINOIS, A CORPORATION OF ILLINOIS.

VISIBLE INDEX.

Application filed March 22, 1924. Serial No. 701,045.

This invention relates to improvements in visible indexes, and refers more particularly to indexes in which the cards are detachably hung in overlapping relation in a frame.

Among the salient objects of the invention are to provide an index sheet or card which is adapted to be detachably mounted on flexible carriers mounted in a frame; to provide a construction of the character described in which a plurality of index cards may be removably mounted on flexible hangers, the latter being removably mounted in a frame, in which a separate detachable index sheet or card auxiliary to the master index cards may be detachably mounted on the flexible hangers, capable of being instantly mounted and removed without disturbing the position of the master cards or their flexible hangers; to provide a construction in which a plurality of said auxiliary index members may be detachably mounted on each hanger; and to provide, in general, a construction of the character referred to.

In the drawings:

Fig. 1 is a side elevational view of a frame having a plurality of index cards mounted thereon in overlapping relation.

Fig. 2 is a fragmentary perspective view of the auxiliary index member and manner of mounting on the hanger.

Fig. 3 is a face view of the auxiliary index member.

Referring in detail to the drawings, 1 designates a frame, of metal or other suitable rigid material, having the central web portion 2 and edge flanges 3 so constructed as to form the vertically extending guide channels 4. One end of the flanged portion 3 may be tubular to accommodate the pintle 5 which is adapted to be movably mounted on a stand, to allow free pivotal movement of the entire frame. It is understood that one or both sides of the frame may take the form shown in Fig. 1 to mount cards on one or both sides thereof. The hangers 6, may take any form of flexible members, but are preferably constructed of flexible wire having return-bent ends 7, which are spaced apart to provide hanger portions 8. The master index member 9 may be provided with the hinge clips 10, which hinge clips engage the ends 8 of the hanger. It is pos-

sible to mount or remove a card 9 by merely bending said card centrally to temporarily contract its length and insert the open portions of the hinge clips 10 on the ends 8, or likewise bend it centrally to remove it from engagement. This, of course, can be done without disturbing the position of the hanger 6. The hanger 6 is instantly mounted in, or removed from, the frame, by likewise bending it centrally, so that the ends 7 are either inserted into or removed clear of the guide channels 4.

Referring to one of the features of the invention, I provide an auxiliary index member 11, preferably of a size slightly smaller than the card 9. The upper corners 70 are preferably cut away and slanted as shown at 12 to obviate any tendency to curl. Adjacent the upper longitudinal edge the member 11 is internally apertured as shown at 13. Any other desired form of aperture 75 may be made. Adjacent one lateral edge, the card or sheet 11 may also be internally apertured as shown at 14 for a purpose hereinafter explained.

The advantages and ease of operation will be immediately apparent to those skilled in this art. For instance, in a business where it is necessary to have a follow-up system, the index card 9 may be designated as the master card to be part of a permanent 85 record, adapted to be retained at all times in the frame. Some provision must be made for allowing the various salesmen who attend to this follow-up work, to have this data for a number of days. The auxiliary 90 sheet 11, carrying the necessary data, is removed from its position in front of the master card 9. The holes 14 are so spaced that they are adapted to engage with the hinges of a standard form of loose-leaf 95 note book carried by salesmen.

When the follow-up has been completed, the auxiliary card can be removed from the loose-leaf book and by bending it centrally so that the ends 8 of hanger 6 slip into the 100 holes 13, can be replaced in the file.

I have illustrated and described one particular use to which my invention may be applied. It will be understood that I do not, in any way, wish to limit it to any particular use or uses, but wish to be protected on the novelty of so mounting an index member, which may be auxiliary to a master

index card, on hangers in a frame, that it can be instantly mounted or removed without disturbing the position of the master cards or hangers.

5 I have described the preferred form as being an auxiliary card. It will be immediately apparent that the card 11 may itself constitute what I term the master card, and a plurality of them may be mounted in overlapping relation, eliminating the use of the index cards 9.

The member 11 may be constructed of any weight fibrous material such as paper, but 15 preferably are lighter in weight and of slightly different color than the master card 9. The members 11 may be of different colors. Two or more differently colored members 11 may be mounted on the same hanger in connection with one master card

20 9. The card 11 may be of any desired weight or thickness, and may be folded along a longitudinal edge to provide a double-sheet card.

I claim as my invention:

25 1. In a visible index, the combination with

a frame, of flexible metallic hangers having return-bent portions adapted to be detachably mounted thereon, master index cards detachably mounted by metallic hinges on the return-bent portions of the hanger, auxiliary sheets having holes adjacent one longitudinal edge also engaging the ends of the return-bent portions, said sheets being removable from said hangers without removing the master cards from the hangers nor 30 the hangers from the frame.

2. In a visible index, the combination with a frame, of flexible spacing hangers mounted adjacent to each other on said frame and having return-bent ends, master index cards 40 mounted by metallic hinges on the return-bent ends of said hangers and auxiliary index sheets provided with hanger-engaging apertures mounted on the return-bent ends 45 of the hangers adjacent said master index cards, said auxiliary sheets being independently mountable on or removable from the return-bent ends of the hangers without disturbing the position of the master card.

WILLIAM CURTIS CLARK.
